DESIGN FOR A FLOWERPOT HOLDER

Hans Peter Hanson, Chicago, Ill.

Application October 1, 1945, Serial No. 122,449

Term of patent 14 years

(Cl. D35—3)

To all whom it may concern:

Be it known that I, Hans Peter Hanson, a citizen of the United States and a resident of Chicago, county of Cook, and State of Illinois, have invented a new, original, and ornamental Design for a Flowerpot Holder, of which the following is a specification, reference being had to the accompanying drawing forming a part thereof, in which

Fig. 1 is a view in side elevation of a flowerpot holder showing my new design; Fig. 2 is a detail sectional view through a part of the holder, as taken on the line 2—2 and on a scale enlarged over that of Fig. 1.

I claim:

The ornamental design for a flowerpot holder, substantially as shown.

HANS PETER HANSON.
